F. R. MARCEL.

HAIR CURLER.

APPLICATION FILED MAY 5, 1919.

Patented Feb. 8, 1921.

INVENTOR
François R. Marcel

BY Charles G. Hensley

ATTORNEY

UNITED STATES PATENT OFFICE.

FRANÇOIS RENÉ MARCEL, OF BROOKLYN, NEW YORK.

HAIR-CURLER.

1,368,181.

Specification of Letters Patent.

Patented Feb. 8, 1921.

Application filed May 5, 1919. Serial No. 294,913.

To all whom it may concern:

Be it known that I, FRANÇOIS R. MARCEL, a citizen of the United States, and a resident of the borough of Brooklyn, in the city and 5 State of New York, have invented certain new and useful Improvements in Hair-Curlers, of which the following is a specification.

My invention relates to the articles called 10 hair curlers in the hair dressing trade. The hair is wound tightly on the curlers while being waved and the present article, though not limited to a particular use, is especially advantageous when used as a curler in permanent hair waving. In the process of waving hair to impart what is known as a permanent wave thereto there are many difficulties encountered one of which is to secure 15 the locks of hair on the curlers tightly. To a great extent the permanency of the wave depends upon the tension or tautness of the hair on the curlers and the object of the present invention is to provide a curler on 20 which the hair may be drawn as taut as desired, thus insuring lasting quality in the wave set in the hair.

Another object of my invention is to provide 25 a curler by means of which the coils of hair may be tightened near the head as well as at the outer ends of the hair.

Another object of my invention is to provide 30 a curler of relatively revoluble members which can be turned in either direction and which may be readily locked in any position against rotation in either direction so 35 that the hair may be wound right hand or left hand and it may be locked securely regardless of the direction in which it is wound on the curler.

Another object of my invention is to provide 40 a more positive lock or clutch for holding the parts of the curler against relative rotation. Another object is to reduce the locking device to the simplest form and to eliminate movable parts and springs.

Another object is to provide a curler 45 which can be very easily manipulated.

In the drawing forming part of this application,

50 Figure 1 is a longitudinal sectional view of my improved curler.

Fig. 2 is an elevation thereof showing the hair wound thereon and ready for tightening and

Fig. 3 is an enlarged sectional view showing the clutch.

The curler, as stated above, is a device around which a lock of hair is to be wound or twisted. The curler shown herein comprises, primarily, two elements which are 60 relatively revoluble. The inner member 1 I shall refer to as a rod though it is not necessary that this should be a solid rod as it may be of tubular form if desired. I prefer, however, to make this member as a solid 65 rod. The second or outer-member comprises the tube 2 which incloses part of the rod and which is adapted to revolve freely around the rod except when the clutch is tightened.

The tube 2 is shorter than the rod 1 and 70 the end 3 of the rod, which is the end nearest the head when the curler is applied, projects beyond one end of the tube and it is slightly flattened at 4. Any means may be employed for securing the hair to the end 4 but I prefer the means shown herein. There 75 is a slot 5 extending inwardly at the end 4 of the rod and slanting somewhat toward the extreme end of the rod. This slot terminates in an enlargement or aperture 6.

The other end of the rod or that end 80 which projects from the tube farthest from the head, is somewhat flattened at 7 so that the rod may be gripped tightly at this point with a pair of pliers.

There is a clutch device for locking the 85 rod and tube against rotation and it operates without a spring. The rod is tapered at 8 to form a cone shaped abutment and this terminates at a shoulder 9 with which latter the end of the tube 2 is adapted to lie flush on the outside, so that the end of the rod and the tube 2 form a continuous smooth surface on the exterior. The end 90 of the tube is made cone shape at the end of the bore as shown at 10 and this is preferably done by reducing the diameter of the tube at this end.

Operation: In using the curler it is 95 brought to a position with the end 3 of the rod near the head and a lock of hair is first secured to the projecting end 3 of the rod.

This may be done as shown, by passing a piece of string 11 around the lock of hair 12 near the head, then passing the ends of the string around the end of the rod and drawing them into the slot 5 so that the hair is drawn tightly against the rod near the aperture 6.

The lock of hair is now wound around the rod and the tube and in this operation the 10 hair may be wound to the left or to the right. It is sometimes desirable to alternate, winding one lock on one curler to the left and an adjacent lock on another curler to the right, to obtain certain effects. When 15 the lock of hair has been wound on the curler the outer end is secured to the tube, one method being to wind a piece of string 13 tightly around the hair and curler. The device is now ready for tightening. The 20 operator grasps the tube 2 with one hand and with a pair of ordinary pliers the flattened end 7 is grasped and then the rod or tube or both are turned to cause a relative rotation of the rod and tube. As the 25 lock of hair is secured at one end to the rod and at the other to the tube the relative rotation of these two members tightens the hair on the curler and sufficient force can be applied to produce any desired degree 30 of tautness. When the hair is sufficiently taut and while the rod and tube are still held, the tube is drawn out slightly in relation to the rod, or, vice versa, the rod is moved inwardly in relation to the tube and 35 the cone shaped clutch members will lock together. The grip on the tube and rod may now be released and the curler will be clutched, with the hair under the desired tension or tautness. It will be noted that 40 the clutch will lock the tube and rod at any point whereas, a pawl and ratchet device will only lock at certain intervals. It is very easy to lock the curler so that the hair is very taut. It will also be noted that the 45 curler may be readily locked regardless of whether the tube is turned to the right or left, which is not so of a pawl and ratchet locking device.

Generally, an electrical heating device is 50 placed over the curler and lock of hair to apply heat to the latter while curled and tensioned, for a period of time sufficient to set the wave or render it permanent; and generally a liquid is used on the hair to 55 secure this result. The heating device is not shown herein as it forms no part of the present invention.

When the heating or baking process has 60 been completed the lock of hair is released from the curler. This may be done by first untying or cutting the strings, but there is this advantage in the present device, that the clutch may be released before removing the tying strings, the operation being 65 quicker and there being less chance of in-

juring the hair. It is only necessary to grip the tube 2 and the rod 1 and force the latter toward the head, at the same time giving it a slight twist. This will release the clutch, and the tube or rod may be freely 70 revolved to unwind the hair.

As it is possible to obtain and maintain the maximum tension in the hair with the present curler it is possible to make a more permanent wave than with the curlers here- 75 tofore used.

If any of the chemicals used in the waving process should reach the inside of the curler it is only necessary to soak or boil the curler in water to clean it and there is 80 no mechanism to be clogged by the chemicals.

Having described my invention what I claim is;

1. A hair curler adapted to be applied 85 near the head for the purpose of having a lock of hair wound and tightened thereon and comprising a tube to which the end of the hair is adapted to be secured, a rod therein and projecting from the end of the tube the projecting end of said rod being adapted to have the hair near the head secured thereto, said tube and rod being relatively revoluble and having male and female cone shaped clutch members adapted to lock 95 said rod and tube for the purpose set forth upon relative longitudinal movement of said rod and tube.

2. A hair curler adapted to be applied near the head for the purpose of having a 100 lock of hair wound and tightened thereon and comprising a tube to which the end of the hair is adapted to be secured, a rod therein and projecting from the end of the tube and to which the hair near the head is 105 adapted to be secured, said tube and rod being relatively revoluble and movable longitudinally, and cone shaped clutch members on said rod and tube near the end which is placed nearest the head and adapted to lock said tube and rod against rotation. 110

3. A hair curler adapted to be applied near the head for the purpose of having a 115 lock of hair wound and tightened thereon and comprising a tube to which the end of the lock of hair is adapted to be secured, a rod revoluble therein, and projecting from the end of the tube, a shoulder on the projecting end of the rod, a cone shaped clutch 120 portion adjacent said shoulder, said tube having a cone shaped clutch portion co-operating with the clutch portion of said rod and adapted to abut against said shoulder, said clutch portions being adapted to lock said 125 tube and rod against rotation.

4. A hair curler adapted to be applied near the head for the purpose of having a lock of hair wound and tightened thereon and comprising a tube to which the end of the 130

lock of hair is adapted to be secured, a rod
revoluble therein and projecting at each end
of the tube, whereby the hair near the head
may be secured to one end of the rod and
5 whereby the other end of the rod may be
gripped, said tube and rod having coöperat-
ing cone shaped clutch portions adapted to

be operated by a relative sliding action be-
tween the tube and rod to lock and unlock
said tube and rod.

10

Signed at the city, county and State of
New York, this 28th day of April, 1919.

FRANÇOIS RENÉ MARCEL.
